UNITED STATES PATENT OFFICE.

SOLOMON SACHS, OF NEW YORK, N. Y.

FOLDABLE TURNTABLE FOR TALKING MACHINES.

Application filed February 26, 1924. Serial No. 695,279.

To all whom it may concern:

Be it known that I, SOLOMON SACHS, a citizen of the United States of America, residing at New York city, county of New York; State of New York, have invented certain new and useful Improvements in Foldable Turntables for Talking Machines, of which the following is a specification.

This invention relates to turn tables and 10 in particular to a turn table adapted to be used with a portable phonograph.

A particular object of the invention is to provide a turn table which may be folded up into a compact position to be stored in 15 a small cabinet phonograph which is carried from place to place.

A further object of the invention is to provide a turn table which may be made of few parts and which can be manufactured 20 cheaply and in quantities.

Referring to the drawing wherein I have shown a preferred embodiment of my invention,

Fig. 1, is a top plan view of a turn table 25 constructed in accordance with my ideas,

Fig. 2, is a similar view of the turn table showing the arms thereof in folded position and the turn table ready for storing, and

Fig. 3, is a section taken on the line 3—3 30 of Fig. 1, showing the construction of the turn table.

Referring to the drawings in detail, 5 indicates a supporting disk having a central bore 6, the disk being projected to form a 35 flange 7, at the center thereof about said bore 6, this flanged portion 7, being of a height equal to the thickness of the supporting arms.

The supporting arms of which there are 40 three, are attached to the disk 5 in spaced relation, the arm 9 being fixedly secured through the medium of two rivets 10 to the disk 5. The cooperating arms 11, are pivoted as at 12 to the disk 5, and are prevented 45 from turning in the directions shown by the

arrow in Fig. 1, by the fixed pins 13, which are secured in the disk 5, and engage the said arms 11, at the sides thereof.

It will be noted in Fig. 3 that the arms can only be opened to a certain position, 50 this position being the one which will afford the most secure and unflexible support for the record which is shown in outline, as at 14.

In Fig. 3, I have also shown a section of 55 phonograph, 15, and the motor operated shaft 16, upon which the disk 5 or turn table may be placed. The central bore of the turn table may be tapered to fit a corresponding taper of the shaft 16, or the disk 60 5, may be provided with a suitable slot in which a pin 17 fastened to the shaft 16, may engage to impart to the turn table the turning movement of the shaft.

All of the arms are provided with rubber 65 or other suitable band members 18, which will prevent slippage of the record relatively to the arms, while the turn table is in motion.

In Fig. 2, it will be noted that the arms 70 11, may be swung around to fold against the arm 8, thus providing a long narrow arrangement which can be stored in a small space in a portable phonograph or the like.

Thus, it will be seen, that I have provided 75 a turn table having few parts and which may be quickly folded or unfolded, and which can be used with a portable phonograph.

Having described my invention, what I 80 claim is:

A turn table comprising a disk member, an arm fixedly connected to said disk member, and a plurality of arms pivotally mounted on said disk member and adapted 85 to move in a plane parallel thereto, said movable arms being adapted to fold parallel to and against said fixed arm.

SOLOMON SACHS.
